UNITED STATES PATENT OFFICE

RUFUS ISENHOUR, OF NEW LONDON, NORTH CAROLINA

ATTACHMENT FOR BRICK MAKING MACHINES

Application filed August 30, 1929. Serial No. 389,533.

This invention relates to an attachment for brick making machines, and it consists in the combinations, constructions and arrangements herein described and claimed.

5 The principal object of this invention is to provide a device which may be attached to any stiff-mud brick making machine for the purpose of giving ordinary stiff-mud, wire-cut or rough surfaced brick the form and appearance of soft-mud, hand-made brick.

Another object is to increase the value of the product of the stiff-mud brick making machine by this means.

A further object is to provide a device of 15 the character described, that will be entirely automatic in its operation.

Other objects and advantages will appear in the following specification, and the novel features of the invention will be particularly 20 pointed out in the appended claims.

This invention is illustrated in the accompanying drawings, forming part of this application, in which:—

Figure 1 is a front elevation of the attachment as viewed from the delivery end of 25 any stiff-mud brick machine to which it might be attached.

Figure 2 is an end elevation illustrating the means of attaching the device to the cut-off table of any stiff-mud brick making machine,

Figure 3 is a vertical sectional view taken along line 3—3 of Figure 1.

Figure 4 is a vertical cross-sectional view 35 taken on line 4—4 of Figure 2, and

Figure 5 is a horizontal sectional view taken on line 5—5 of Figure 1.

Referring to the drawings, there is shown a rectangular base-plate 6, constructed preferably of steel, at the opposite ends of which are rigidly attached two vertical members 7 and 8. A horizontal brace 25 is secured to the vertical members 7 and 8 and is adapted to give added strength to the device.

45 Supported by said vertical members and attached thereto, are a cover 9 and a sand-hopper 10. There are also attached to the vertical members 7 and 8, a front wall 11 and a rear wall 12, constituting a chute. Mounted upon the rear wall 12 and at equidistant

points thereon are division blocks 13, pointed at their upper ends to facilitate the movement of sand from the hopper 10 through channels 16, between the aforesaid division blocks.

55 Directly below the front wall 11 and extending between the vertical members 7 and 8 is a horizontal bracket 14 having a downwardly extending vertical arm 15, which is rigidly attached to the division blocks 13.

On the inner sides of the vertical members 7 and 8 are attached guide-blocks 17 and 18, respectively. Slidably mounted between the guide-blocks 17 and 18 and the arm 15, is a block 19, beveled sharply toward the front 60 of the device, as shown in Figures 2 and 4.

To the beveled face of the block 19 is attached a steel plate 20, and rigidly mounted in said block are two vertical upwardly extending bars 21 and 22, which are slidably 65 arranged in the openings in the bracket 14.

Encircling the bars 21 and 22 and acting against the under side of the horizontal bracket 14 and the top side of the block 19 are compression-springs 23 and 24, respectively. 70

Blocks 26 and 27, beveled sharply toward the front of the device, are slidably mounted adjacent to the base 6 in suitable openings in the vertical members 7 and 8, respectively.

75 Rigidly mounted in the blocks 26 and 27 are outwardly extending bars 30 and 31, respectively, which are slidably arranged in suitable openings in U-shaped brackets 32 and 33, having laterally extending arms 34 and 35 attached by means of bolts 36 to the vertical members 7 and 8, respectively.

80 Compression-springs 37 and 38 encircle the bars 30 and 31 and bear against the blocks 26 and 27, and the inner sides of the brackets 32 and 33, respectively.

In all the views, the numeral 39 denotes a moving column of clay from any ordinary stiff-mud brick-making machine equipped for making wire-cut or rough surfaced brick.

85 In Figure 2, a conveyor-belt 40 is shown in operative position for carrying away the column of clay 39, after treatment by the device, to a cutting-table, not shown.

The operation of the device is as follows: 90 A quantity of sand is placed in the hopper 10.

This sand finds its way down by gravity through the channels 16 to the top and sides of a moving column of clay 39 from a stiff-mud brick-making machine equipped for 5 making wire-cut or rough surfaced brick.

As this column moves through the device, the surface of the column is further roughened and textured and the sand is forced into its surface by the steel-faced blocks 19, 26 10 and 27, which are held forcibly against the column by the action of the springs 23, 24, 37 and 38.

By employing the vertical division members 18 to form a plurality of relatively 15 narrow channels or passageways therebetween, the granular material or sand is distributed over the top and opposite side surfaces of the brick stock in a relatively thin layer which is to be readily forced into 20 the said surfaces by the pressure of the members 19, 26 and 27 as aforesaid.

The conveyor-belt 40 then carries the now roughened, textured and sanded brick to its next operation.

25 It will be noted that the whole operation of the device is automatic, it merely being necessary to keep a supply of sand in the hopper.

It is obvious that many changes in construction might be made without departing 30 from the spirit and scope of the invention.

What is claimed is:

1. In a device of the class described a base 35 plate, a material receiving hopper rising from said base plate and having openings through its front and rear sides for the passage of a length of stiff-mud brick stock therethrough as it is moved along said base plate, and a plurality of vertical division members arranged 40 in spaced relation within said hopper to provide relatively narrow passageways between the same for the continuous feed of material downwardly therethrough for deposit in a relatively thin layer on the brick stock during 45 its passage through the hopper.

2. In a device of the class described, a base 50 plate, a material receiving hopper open at its lower end and supported immediately above said base plate, said hopper having openings through its front and rear sides for the passage of a length of stiff-mud brick stock therethrough as it is moved along said base plate, and a plurality of vertical division members arranged in spaced relation within 55 said hopper to provide relatively narrow passageways between the same for the continuous feed of material downwardly therethrough for deposit in a relatively thin layer on the top and opposite side surfaces of the brick stock during its passage through the hopper.

3. In a device of the class described, a base 60 plate, a material receiving hopper open at its lower end and supported immediately above said base plate, said hopper having openings

70 through its front and rear sides for the passage of a length of stiff-mud brick stock therethrough as it is moved along said base plate, and a plurality of vertically extending division members arranged in spaced relation within said hopper to provide relatively narrow passageways between the same for the continuous feed of material downwardly therethrough for deposit in a relatively thin layer on the brick stock said division members having oppositely beveled top edges to facilitate the uniform downward discharge of the material through said passageways.

4. In a device of the class described, a base 75 plate, a material receiving hopper, a relatively narrow chute depending from the lower discharge end of said hopper and supported on said base plate, said chute being open at its lower end and having openings in the front and rear side walls at the lower ends thereof for the passage of a length of stiff-mud brick stock therethrough as it is moved along said base plate, and a plurality of vertically extending division members arranged in spaced relation within said 80 chute to provide relatively narrow passageways between the same for the continuous feed of material downwardly therethrough for deposit in a relatively thin layer on the top and opposite side surfaces of the brick 85 stock during its passage through the chute, said division members having their top edges oppositely beveled to facilitate the downward discharge of the material from said hopper and into said passageways.

5. The device as set forth in claim 4 and having a presser block mounted in a cutout in the lower edge of the front wall of said chute and adapted to act on the top surface of the brick stock to force the material from said chute into the said surface, and other presser blocks projecting inwardly of the opposite side walls of said chute and adapted to act on adjacent side surfaces of the brick stock to force the said material into such surfaces, all of said blocks having their inner 100 ends beveled in a rearward direction to cause an even distribution of the material from said chute over the said surfaces of the brick 105 stock.
